UNITED STATES PATENT OFFICE

CLARENCE D. BALDWIN, OF BELLINGHAM, WASHINGTON

SPLICE BAR

Application filed October 22, 1928. Serial No. 314,067.

My invention relates to improvements in splice bars more especially for use on the rails of logging rail roads.

The practice in logging heavy timber in the North West is to not only build a rail road from the shipping point to the timber but also to build spur rail roads into the timber to which logs are brought on overhead cables from as wide an area as practicable. When such an area is logged off the rails and ties of the spur road are taken up and used in building another spur road into the timber of an adjoining area.

Because of the temporary nature of the service required of these spur roads they are not put down with the care and thoroughness accorded the laying of rail roads for longer periods of use.

The heavy traffic on these spur roads is one-way and the rail "creeping" due to braking the heavy logging trains passing thereover is considerable. This is especially true when the spur roads are on steep hillsides from which much of the timber logged is now being taken.

No successful way has been found to stop this rail movement and it is accepted as unavoidable.

When the ties are prevented from "creeping" laterally with the longitudinal creeping of the rails and the rails are fastened thereto in a manner to prevent the rails from "creeping" over such a tie, it not infrequently happens that such a tie is forced to roll beneath the rail and cause a bend in the rail sometimes resulting in train derailment.

The splice bars, or fish plates, are most frequent causes of these objectionable tie displacements. While it is not the practice on spur logging rail roads to drive spikes in the notches usually provided in the flange edges of splice bars, the spikes being driven along the straight edges thereof; yet the ends of the flanges of the splice bars are square and these ends abut the spikes in the adjacent tie when the same is reached due to rail "creeping" and sometimes cause this tie to roll beneath the rail with consequent track displacement. Also it sometimes happens that pressure from the flange ends will bend the

spikes over and the flanges may then pass on top thereof and cause a displacement difficult to repair.

This improvement has for an object to provide a splice bar which will pull and bend backward from the rails the rail spikes which the ends thereof reach during the "creeping" of the rails. 55

I attain this and other objects of my improvement with the device illustrated in the accompanying sheet of drawings, forming a part of this specification, in which Figure 1 is a side elevation of my splice bar, Fig. 2 is an end elevation of Fig. 1 and Fig. 3 is a plan view of the abutting ends of two rail road rails joined with two of my splice bars in place on the ties of a rail road with the remainder of the rail road broken away. 60 65

Similar characters refer to similar parts throughout. 70

With more particular reference to the designated parts: My splice bar consists of web 4 with bolt holes a^4 therethrough and flange 5 with diagonal ends 6, 6 having beveled edges 7, 7. 75

In Fig. 3 rails 8, 8 with flanges a^8 abut and are joined by splice bars 4, 5 and 4, 5. The spliced rail ends are mounted on ties 10, 10, 10 held in place thereon by spikes 11. Said splice bars are clamped to the rails by 80 bolts 9.

Now assume that the rails are caused to very slowly move over the ties and beneath the spike heads. Eventually one of diagonal beveled edges 7 will pass beneath the head 85 of one of spikes 11 and slowly pull the spike as it shoves it backward away from the rail flange. Later the spike head on the opposite rail flange will be reached by the beveled diagonal forward end of the splice bar on 90 the other side of the rail and this spike also will be lifted and forced outward from the rail and, if the situation is not corrected, the continued rail "creeping" will force these spikes outward till the full-width parts of 95 the flanges of the splice bars are on the tie in which said spikes are driven.

Because the spikes are first lifted before being forced outward by the beveled diagonal flange ends their slow displacement may 100

occur without exerting so great a lateral force on the tie that it may retain its operative position beneath the rail. In due time, of course, the track repair crew discovers the displacement of the spikes and make repairs, which, in this case, are not unusually difficult.

Having thus disclosed my invention, what I claim as new therein and desire to secure by Letters Patent is,—

10 A rail-road rail splice bar consisting of web and flange members the ends of said flange member disposed diagonally toward the center thereof and beveled from the top outward toward the bottom thereof providing a chisel edge on each end of said flange member adapted to bear flatwise on a cross tie and the outer edge of said flange member having neither notches nor other spike-engagement means therein.

CLARENCE D. BALDWIN.
